Des. 225,458
Patented Dec. 12, 1972

225,458

COMBINED TELESCOPIC SIGHT AND GUN MOUNTING

Rolf Heym, Kreis Kissingen, Coburger Strasse 8,
Munnerstadt, Germany

Filed May 13, 1970, Ser. No. 22,953

Term of patent 14 years

Int. Cl. D16—06

U.S. Cl. D57—1

FIG.1

FIG.2

FIG.3

FIG.4

FIG. 1 is a side elevation of a combined telescopic sight and gun mounting showing my new design;

FIG. 2 is a front elevation thereof;

FIG. 3 is a front perspective view with portions omitted for convenience of illustration; and

FIG. 4 is a bottom perspective view thereof.

The broken lines are shown for illustrative purposes only.

I claim:

The ornamental design for a combined telescopic sight and gun mounting, as shown and described.
